WEB-HEATING DEVICE

Karl L. Dietrich, Philadelphia, Pa., assignor to
 Selas Corporation of America, Philadelphia,
 Pa., a corporation of Pennsylvania

Application April 27, 1948, Serial No. 23,565

15 Claims. (Cl. 263—3)

1

The present invention relates to the treatment of a continuously moving web of material by heat, such as the drying of ink on a printed web or the singeing of a textile web, or for other purposes. The invention will be described herein in connection with the drying of ink on a printed web since that is a usual application to which apparatus of this type may be placed. It should be understood, however, that the described application is only one example of where the device may be used.

In color printing in modern web presses the web is first given one impression and then dried before passing directly to receive a second impression. The drying must take place in a short period of time and while the web is moving at a relatively high speed. During the drying operation, as well as during the printing, care must be exercised to maintain the web under constant tension across its entire width to reduce the tendency for a web break. The tension of the web also enters into the problem of maintaining a constant length of web between each pair of impression rolls so that proper register occurs when two or more colors are being used. With the many problems encountered in handling the web itself has been added that of placing drying ovens in the path of web travel between the pairs of impression rolls. The dryers heretofore used require a large amount of space in a relatively crowded area. They also make it difficult to thread the press, and particularly, so when a web break occurs after the dryers have been in use. Since the web passes through the oven in proximity to the burners thereof, there is always the danger of a fire when the press is stopped.

With the dryer of the present invention provision is made to move the web into and out of the oven as the press is being started and stopped. The arrangement is such that the length of the web is not altered, and the tension of the web is not varied as the moving thereof is taking place. The oven that is used with the present invention is U-shaped, and therefore does not require as much room in the press as does the conventional oven. The entire dryer assembly is compact and may easily be placed between groups of impression rollers.

Since the web is moved out of the oven when the press is stopped or when a web break occurs the likelihood of a fire is reduced to a negligible extent. Also, the difficulty of rethreading the press after a web break is reduced since the operators do not have to pass the web through a hot oven.

It is an object of the invention to provide a web dryer in which the web may be moved into and out of the oven thereof either automatically in response to operation of the machine with which the dryer is being used, or manually. It is a further object of the invention to provide a web dryer in which the web may be moved to and from the oven thereof without altering the tension of the web or the length of the web extending between operating parts of the machine with which the dryer is used.

It is a further object of the invention to provide a web dryer through which the web may be easily and conveniently threaded, and one in which the fire hazard is greatly reduced.

It is a further object of the invention to provide a method of drying a moving web. The method comprises moving the web into and out of a heating zone in accordance with various operating conditions of the machine that is operating on the web.

It is a further object of the invention to provide a method of shifting a web into and out of a heating zone without altering its length or varying its tension.

The various features of novelty which characterize my invention are pointed out with particularity in the claims annexed to and forming a part of this specification. For a better understanding of the invention, however, its advantages, and specific objects attained with its use, reference should be had to the accompanying drawings and descriptive matter in which I have illustrated and described a preferred embodiment of the invention.

In the drawings:

Figure 1 is a view showing the entire dryer assembly with the control valve in section;

Figure 2 is a view taken on line 2—2 of Figure 1;

Figure 3 is a view taken on line 3—3 of Figure 1;

Figure 4 is a diagrammatic view of a different embodiment of the invention; and

Figure 5 is a partial view of another embodiment of the invention.

For purposes of the present description the applicant's drying device is described as being used in connection with a printing press to dry ink that has been placed upon a continuously moving web. In Figure 1 there are shown cross pieces 1 of a press that are separated by a vertical post 2. The drying device is mounted on the press between the cross pieces 1. The web W is brought in from above as indicated at 3 and passes in one loop around a roller 4 and in another

2

loop around a roller 5. Both rollers are mounted on a movable carriage 6. From roller 5 the web is led around water cooled rollers 7 and 8 where it leaves the device at 9 on its way to another pair of impression rollers to receive additional ink or to some other part of the press. In its path through the drying device, as it moves around roller 4, the web passes through an oven 11 that supplies the heat to dry the web.

Carriage 6, mentioned above, consists of a pair of side plates 12 and 13 shown best in Figures 2 and 3 that are suitably joined together so that they move in unison. The carriage and the rollers 4 and 5, mounted thereon, are moved in a vertical direction to carry the loop of web into and out of the oven depending upon whether drying is to take place or not. In order to guide the carriage as it moves through the oven there are provided four guide rolls 14 located in pairs on each of the side plates. These rollers move vertically in tracks 15 that are attached to structural steel members 16 which form the framework for the entire device, best shown in Figures 2 and 3. The rollers 14 are mounted in bearing supports 17 which are, in turn, located on brackets 18 fastened respectively to the side plates. Thus the entire carriage is guided by eight rollers, four on each end so that it may move vertically in the tracks 15 to move the web into and out of the furnace. It is noted that the water cooled rollers 7 and 8 are mounted in bearings 19 and 21, respectively, which are attached to two structural members 16. These latter members, of course, are stationary so that the water cooled rollers remain in a fixed position relative to the other parts of the press.

It is essential that side plates 12 and 13 move exactly the same amount in order to prevent the rollers 4 and 5 from being tipped so that the web has more tension placed on one edge than on the other. To insure that the carriage moves absolutely vertically, there is provided a shaft 22 which has pinions 23 on each end of it. These pinions mesh with the teeth of racks 25 which are attached to one of the vertical structural members 16 on each side of the device. The shaft 22 is journaled in bearings 26 that are mounted on brackets 27, one of which is fastened to each side plate 12 and 13. Thus, as the carriage is moved in a vertical direction, the pinions roll up and down the racks 25 to insure that both sides of the carriage move exactly the same amount. The same brackets 27 upon which bearings 26 are mounted are used to support bearings 29 for a shaft 28 upon which the roller 5 is mounted. Thus, the roller is mounted so that it can rotate in bearings which move along with the carriage. Roller 4 is provided with a shaft 31, as shown in Figure 3. This shaft extends through the side plates 12 and 13 where it is journaled in bearings 32 that are mounted on brackets 33 which, in turn, are fastened to the respective side plates of the carriage.

The carriage is shown as being moved in a vertical direction by a fluid means. To this end cylinders 34 and 35 are mounted on the framework of the device, one on each side of the carriage, as best shown in Figure 2. The cylinders are provided with piston rods 36 and 37 respectively, which extend downwardly and are attached to the side plates. One such attachment is shown at 38 in Figure 1. Fluid is supplied to the opposite ends of the cylinders, as best shown in Figure 1 by means of pipes 39 and 41 respectively. When fluid is admitted through pipe 39

the piston rods move downwardly to move the carriage to the position shown in Figure 1, with the web in the oven. When fluid is admitted through pipe 41 the piston rods are moved upwardly to move the carriage upwardly and carry the web out of the oven. When this occurs the rollers 4 and 5 take the position shown at 4' and 5' respectively. It will be noted that the roller 4 is then above the top edge of the oven and out of the heat that is produced by the oven.

Referring now to Figures 1 and 3, it will be seen that the oven is U-shaped and includes two panels 42 and 43 which are mounted on opposite sides of the roller 4 and joined at their lower ends. Each of these panels is provided with a series of burners of a type, for example, similar to those disclosed in detail in Hess Patent 2,215,079, granted September 17, 1940. Each of these burners is supplied with a combustible gas mixture through a tip 45 that extends into a cavity 44 of the burner. As the gas is burned in these cavities the surface of the cavities are heated to incandescence to supply radiant heat to the web as it is moving past them. It is noted that each of the tips 45 is supplied through a pipe 46 which is connected to a manifold 47. Each of the pipes 46 is provided with a valve 48 so that the burners can be adjusted individually to give the desired pattern of heat over the web. For example, if a narrow web is being fed through the press, it will only be necessary to use those burners facing the web. The other burners may be turned off and thus save fuel and reduce the likelihood of overheating of the web. It will be seen that the radiant panels 42 or the sides of the oven are separated by slots 49 and 50 respectively through which shaft 31 of roller 4 moves as it is shifted to bring the web into and out of the oven.

Manifolds 47 supplying the individual burners are in turn supplied by a pipe 52 that has in it an automatically controlled valve 54 around which is placed a by-pass 55 having a manually controlled valve 56 in it. In the normal operation of the oven, when the press is running, valve 54, which is shown as being a solenoid valve, is energized to open pipe 52 so that the combustible gas mixture may flow to the burners. The energizing circuit for valve 54 is connected in any suitable manner with the energizing circuit for the press itself so that when the press is running valve 54 is open. When however, the press is stopped for some reason, valve 54 will be de-energized to shut off the supply of gas and cut down the heat of the oven. This prevents overheating of the oven when no web is to be dried, and acts as a safety control to insure that overheating will not take place. During the time valve 54 is closed a certain predetermined amount of fuel can pass through the valve 56 to keep the oven at a minimum desired temperature. Since the burners are kept running at a low rate it will prevent the oven from cooling down entirely; therefore when the press is re-started and the fuel gas supply is passed to the oven, the oven will heat up and be in condition to dry the web by the time the web is moved into the oven. It is noted that an exhaust duct 60 is provided at the upper ends of each heating panel 42 and 43 so that the exhaust gases from the oven may be drawn off before they can overheat the other parts of the dryer.

As noted above, carriage 6 is moved in a vertical direction to bring the web into and out of the oven by the admission of fluid to one end or the other of cylinders 34 and 35. In Figure 1 there is illustrated a valve arrangement whereby

the flow of fluid to the opposite ends of the cylinders can be controlled. The upper end of both cylinders 34 and 35 will be supplied by pipe 39 whereas the lower end of both cylinders will be supplied by pipe 41. There is shown a piston type valve 57 which is supplied with fluid under pressure through an inlet 58. The valve chamber has located in it a piston rod 59 on which are placed pistons 61 and 62. The piston valve may be held in its upper position against the force of a compression spring 63 by a solenoid core 64 which is controlled by a solenoid 65. When in this upper position, as shown in the drawing, pipe 39 is connected with supply pipe 58 and pipe 41 is connected with the exhaust through a throttle valve 67. When the piston valve is moved downwardly pipe 41 is connected with supply 58 and pipe 39 is connected with the exhaust through a throttle valve 66. Valves 66 and 67 are used in the exhaust lines to control the speed of movement of the piston. By adjusting these valves to control the rate at which fluid may be exhausted from the piston the rate of movement of the piston can be adjusted. For example, if valve 67 is closed more than valve 66 fluid will be exhausted from the lower ends of the pistons slower than it will be exhausted from the upper end. Therefore the web will be moved into the oven slower than it will be moved out of the oven.

A shield 70 is provided in order to prevent the web passing around roller 4 from being subjected to direct radiation of heat from the oven space between sides 42 and 43 when the roller 4 is in its upper position. The shield 70 is formed as a rectangular plate of heat insulating material that is slightly larger than roller 4, as shown in Figure 3. Projections extend from the ends of the plate through extensions of slots 49 and 50, below roller 4. These projections are securely fastened to the side plates 42 and 43.

It is intended that solenoid 65 will be connected with the energizing circuit of the press as was solenoid valve 54 which controls the supply of fuel to the oven. In this fashion when the press is operating solenoid 65 will be energized and the piston valve will be so adjusted that the carriage is moved to its lower position as shown in the drawing, and the web will be in the oven being dried. When, however, the press is stopped solenoid 65 will be de-energized and the piston valve will be moved to its lower position by spring 63. At this time fluid will be admitted to the lower end of the cylinders 34 and 35 and the carriage will be moved upwardly to carry the web out of the oven.

In Figure 1 there is shown schematically one way of controlling the press drive means, which is indicated as a motor 53, along with valve 54 and valve 57. There is shown a normally open solenoid switch 20 which is closed against the force of a spring by a solenoid coil 20a. The solenoid coil is connected across the line and is energized or de-energized by the closing or opening of a manually operated switch 20b. Mounted on the plunger of switch 20 is one pair of contacts 53a in the wires leading to press motor 53. There is also provided a second pair of contacts 65a in the wires leading to solenoid 65 and valve 54. Thus, when the press drive motor is started the supply of fuel to the oven will be turned on and the loop of web around roller 4 will be moved into the oven at a speed determined by the adjustment of valve 67.

Manual operation of solenoid 65 may also be accomplished at any time when for some reason

it is necessary to move carriage 6 independently of the operation of the press. To this end there is located across the leads to solenoid 65 an energizing circuit including a manually operated switch 68 that when closed can be used to energize the solenoid by connecting it directly to the line. There is also provided a switch 69 in the circuit for solenoid 65 which is normally closed. This switch can be opened manually at any time, however, in order to de-energize solenoid 65 and to permit the carriage to move upwardly to bring the web out of the oven, if for any reason this should be desired during the time the press is in operation.

Assuming that the press has been stopped, solenoid valve 54 is closed so that only a small amount of gas is supplied to the burners in the oven through by-pass 55, with the result that the oven is warm but is not supplying enough heat to dry a web. During the time that the press is stopped solenoid 65 is de-energized and the piston valve 57 is in its lower position so that the carriage is raised to bring the web out of the oven. In this position the web may easily be threaded in the press without the necessity of an operator running the web through the oven. When the press has been threaded and everything is in readiness, the press will be started. Simultaneously with the starting of the press solenoid valve 54 is opened to supply the full amount of fuel to the oven and the oven will therefore quickly come up to temperature. At the same time solenoid 65 is energized to move the piston valve 59 to its upper position. This permits fluid to flow through pipe 58 and pipe 39 to the upper end of the cylinders 34 and 35. Therefore the carriage 6 will be moved downwardly to decrease the size of the web loop around roller 4 and increase the size of the web loop around roller 4 at a rate dependent upon the adjustment of valve 67. This valve may be so adjusted that by the time the carriage reaches its lower position, shown in Figure 1, the oven will have reached its normal operating temperature and the web will be properly dried as it is being moved through the furnace. When the press stops solenoids 54 and 65 will be de-energized to cut down the fuel to the oven and to move the web upwardly out of the heat, decreasing the size of the loop around roller 4 and increasing the size of the loop around roller 5.

From the above description it will be seen that the entire drying unit is compact and occupies a relatively small space that can be obtained in the average printing press. Because of the fact that the web is dried while moving both downwardly and upwardly in a loop only a short oven is necessary. The same amount of heat can be applied when drying the web as it moves in two directions that could be obtained with a long oven that is located on one side only of the web. It is only necessary to use the burners in one panel, however, if they produce all of the heat required for a given operation. Since rollers 4 and 5 are both mounted on the carriage and move in unison, the total amount of web that is passing through the dryer will not be varied as the carriage is moved from one position to another. Therefore neither the register of the web nor its tension will be disturbed due to movement of the carriage while bringing the web into and out of the oven. While the entire dryer mechanism has been shown mounted for operation in a vertical direction, it will be apparent that it could be just as easily mounted for operation in a hori-

zontal direction. This will depend upon the construction of the machine with which it is used. In the above described embodiment of the invention the loops of web are moved in a single direction. In some cases it may not be possible to obtain the necessary space for this operation. In such cases an arrangement similar to that shown in Figure 4 may be used where the slack for the loop moved out of the oven is taken up at an angle to the oven. Referring to that figure, it will be seen that the web *W* passes into the oven as a loop around the roller *71* and back upwardly over the water cooled rollers *7* and *8*. In its path of travel the web passes on opposite sides of second roller *72* that is in line with the loop. Roller *71* is mounted in a carriage that comprises journals *73* located at each end thereof, which have threaded portions that are received on threaded shafts *74*, only one of which is shown. These shafts extend in a vertical direction and are mounted for rotation in bearings *75*. Roller *72* is mounted on a shaft which is received in journals *76* that are threaded to horizontally extending threaded shafts *77*, only one of which is shown. These latter shafts are mounted for rotation in bearings *78*. The shafts *74* and *77* are moved simultaneously, to move rollers *71* and *72*, by a motor *79* that may be connected directly to one shaft *78*, as shown in the drawing, or may be connected to that shaft through a suitable clutch. Shaft *77* serves to drive shaft *74* at the same rate of rotation through bevel gears *81* and spur gears *82*. Suitable gearing is provided to drive the threaded shafts on the other side of the device. It is noted that guide rollers *83* and *84* are provided to direct the web in a horizontal loop as roller *72* is moved to the right in the drawing. Motor *79* is controlled in its direction of rotation by a switch *85*. This switch has a rod *86* upon which are mounted an upper contact bar *87* and a lower contact bar *88*. The switch bar is moved in an upwardly direction by spring *92* and is moved downwardly by a core *89* of a solenoid coil *91*. This coil is connected in the circuit for the press operation as was coil *65* of the piston valve *57* of Figure 1. Also connected in circuit with solenoid coil *91* is a switch *93* by means of which the solenoid can be energized independently of press operation, and a manually operated switch *94* by means of which the solenoid can be de-energized independently of press operation.

The operation of this dryer unit is substantially the same as that described above. Normally when the press is running the various rollers are in the positions shown in the drawing with the web passing through the oven to dry the ink thereof. When the press stops or the solenoid *91* is de-energized for some other reason, contact bars *87* and *88* will move out of engagement with the lower contacts and into engagement with the upper contacts. This reverses the direction of rotation of motor *79* to move roller *71* upwardly and roller *72* to the right to the dotted line position shown. The web is therefore moved out of the oven so that burning of the web will not occur. It is noted that suitable limit switches can be incorporated in the motor circuit to limit the amount of movement of the rollers *71* and *72* in either direction.

It will be seen that the embodiment of the invention disclosed in Figure 4 operates in exactly the same fashion as that shown in Figure 1 except that the loop of web which is created when the web is moved out of the oven is taken up at

an angle to the oven. In each case the web is moved out of the oven to facilitate threading of the same through the press and to prevent burning of the web in the event that the press is stopped. In each case the length of web in the dryer unit is the same and the tension of the web is not altered at any time. It will be apparent that fluid means similar to that disclosed in Figures 1 to 3 may be used to move the rollers *71* and *72* of Figure 4 instead of the mechanical means shown therein, if it is so desired. Likewise the mechanical means used to move the rollers of Figure 4 may be used to move the carriage upon which the rollers *4* and *5* of Figure 1 are mounted, if it is so desired.

In each of the embodiments of the invention described above the two movable rollers over which the web passes have been mounted for movement together. This is believed to be the preferred type of operation. In some cases, however, it may be desirable to have the rollers over which the web travels moved independently. Such a construction is shown in Figure 5 wherein it is intended that the web shall pass around a vertically movable roller similar to roller *71* in Figure 4. In its travel the web passes on opposite sides of a roller *72a* corresponding to roller *72*. In this case roller *72a* is mounted in journal blocks *76a* that are slideable on shafts *77a*, only one of which is shown. Roller *72a* is biased toward the right by a cable *95* which passes over a pulley *96* and has a weight *97* or some other constant force acting on its end.

This embodiment of the invention acts to reduce the size of one loop of web while the size of a second loop is increasing as does the other embodiments. Here, however, the two rollers which form the loops are not mechanically connected together. One of the rollers is moved by the application of power from a suitable source while the other is moved by a constantly acting force to take up or supply the necessary slack while maintaining the web under a constant tension.

While in accordance with the provisions of the statutes I have illustrated and described the best form of embodiment of my invention now known to me, it will be apparent to those skilled in the art that changes may be made in the form of the apparatus disclosed without departing from the spirit and scope of my invention, as set forth in the appended claims, and that in some cases certain features of my invention may be used to advantage without a corresponding use of other features.

55 What is claimed is:

1. In a web heating device, the combination of an oven including a pair of oppositely disposed heating sections with a space between said sections and a narrow slot extending through opposite sides of said oven at each end of said space, a roll of a size to be received in said space, a shaft for said roll extending through said slots, bearings for said shaft outside of said space, and means to move said bearings in the direction of said slot to bring said roll into and out of said space.

2. In a web heating device the combination of a first roller and a second roller over which the web is passed in a pair of loops, means to move simultaneously said rollers to increase the size of one loop and decrease the size of the other loop whereby the total length of web in said loops and the tension thereof will not be changed, an oven to heat said web, and means to locate

said oven in a position to receive said first loop as it is being increased in size.

3. In a web heating device, the combination of a first roller, a second roller, the web to be heated being threaded around said rollers to form a pair of loops, means to mount said rollers for movement through paths of the same length, means to move simultaneously said rollers through said paths to lengthen one loop while shortening the other, and an oven for heating said web located so that one loop is moved into and out of heating relation with respect to said oven as it is lengthened and shortened.

4. In a web heating device the combination of a carriage, means to mount said carriage for movement through a path, a pair of rollers mounted for rotation in spaced apart position on said carriage, the web being threaded around said rollers to form a loop, means to move said carriage through its path to shift the position of said loop, a web heating device, and means to mount said device along the path of travel of said loop whereby the web in said loop will be heated by said heating device when in one position thereof.

5. In a web heating device, the combination of a frame, tracks on said frame, a carriage, guide rollers on said carriage received in said tracks, a web guiding roll on said carriage around which the web is passed in a loop, a cylinder mounted on said frame adjacent to each side of said carriage, a piston received in each cylinder with a piston rod extending therefrom, means to attach the outer ends of said piston rods to opposite sides of said carriage, means to control the flow of an actuating fluid to opposite ends of said cylinders to reciprocate said carriage and thereby move said loop, and an oven located in the path of movement of said loop whereby said loop will be moved into and out of said oven as said carriage is reciprocated.

6. In a web heating device, the combination of a carriage, means to mount said carriage for reciprocating movement, a pair of guide rolls mounted on said carriage and around which the web is to be threaded in a loop extending in the direction of carriage movement, a U-shaped oven having a space therein opening at one end thereof of a size to receive the roller on the carriage around which the web is looped, means to mount said oven in a position where said last-mentioned roll will be received in the space in said oven at one end of the movement of said carriage, and means to move said carriage from a position in which said roll is in said space to a position in which said roll is withdrawn therefrom.

7. In a web heating device the combination of an elongated carriage, means to mount said carriage for reciprocating movement, a first guide roller located near one end of said carriage, a second guide roller located near the opposite ends of said carriage, an exit roller mounted adjacent to said second guide roller when said carriage is at one end of its path of travel, the web being threaded from a point in line with the direction of travel of said carriage around said first roller and in an opposite direction around said second roller and in the first direction to pass around said exit roller whereby as said carriage is moved the position of the guide rollers will be changed without changing the length of the web passing around them, means forming a heating zone into which said first roller is moved when said carriage is at said one end of its path of travel, and means to move said

carriage to bring said first guide roller into and out of said heating zone.

8. In a web heating device, the combination of an oven comprising a U-shaped structure with a pair of opposed heating members forming the legs of the U, said members forming an enlarged space with narrow slots at the edges thereof, the slots extending in the direction of said members, a web guiding roller having a shaft projecting from the ends thereof, said roller being of a size to be received in said space with the ends of the shaft projecting through said slots, mounting means for the ends of said shaft, and means to move said mounting means to carry said shaft through a path from a position in which said roller is out of said space to a position in which said roller is at the bottom of said space away from the open ends of the legs of the U whereby a loop of web passing around said roller may be moved into and out of the heating zone between said members.

9. In a web heating device, the combination of an oven having an opening therein, a first roller over which the web is to be passed in a loop, a second roller normally located in a position between the sides of the loop, means to move said first roller into and out of the opening in said oven, means to move said second roller in a path at an angle to that through which said first roller moves, and operating mechanism for said moving means to move said first roller into said opening and said second roller to its normal position or to move said first roller out of said opening and said second roller through its path away from said normal position.

10. In a web heating device, the combination of a first pair of parallel threaded shafts, a first roller, bearing for said roller threadedly mounted on said shafts, a second pair of parallel threaded shafts extending at an angle to said first pair of shafts, a second roller, bearings for said second roller threadedly mounted on said second pair of shafts, means to rotate simultaneously said pairs of shafts to move said rollers along the same, the web to be dried being threaded around said rollers in a pair of loops that are increased and decreased in size respectively as said rollers are moved in opposite directions, and an oven located to receive one roller and the web passing around it as said roller is moved in a direction to increase the length of its loop.

11. In a web heating machine, the combination of a machine operating on the web, an oven to heat the web, guide means over which the web is threaded in a loop, means to move said guide means into said oven whereby the web loop will be heated and out of said oven, operating means to start and stop said machine, operating means for said means to move, and means to control simultaneously said two operating means whereby as said machine is started said means to move will carry said web loop into said oven and as said machine is stopped said operating means will carry said web loop out of said oven.

12. The method of moving a travelling web into and out of a heated zone which comprises passing the web while it is moving through a first loop and a second loop, changing the lengths of said loops by increasing the length of one while decreasing the length of the other the same amount, and moving the first loop into a heated zone while it is increasing in length and out of said heated zone while it is decreasing in length.

13. The method of moving a travelling web into and out of a heating zone which comprises

11

continuously feeding the web through a path that includes a first and a second loop extending in different directions, increasing the size of the first loop and simultaneously decreasing the size of the second loop the same amount, and passing the first loop into a heated zone as it increases in size and removing said first loop from the heated zone as it decreases in size.

14. The method of moving a traveling web into and out of a heated zone which comprises passing the web in a first loop extending in one direction and a second loop extending in a second direction, changing the lengths of the loops by simultaneously increasing the length of one loop while decreasing the length of the other 15 the same amount, moving the first loop into a heated zone while it is increasing in length and out of said heated zone while it is decreasing in length, and controlling the movement of said loops in response to the operation of a machine 20 that is acting on the web.

15. In a device for heating a continuous length of strip material, the combination of structure forming a heating zone past which the strip material moves, supporting and guiding means, a 25 carriage mounted on said means for movement

5
10

in a path from a position in said heating zone to a position outside of the same, a pair of spaced and parallel guide rollers on said carriage, a stationary guide roller, the strip material passing in a pair of reversely directed loops around said pair of guide rollers on said carriage and said stationary guide roller, and means to move said carriage through its path to carry the strip material guided by the rollers thereon into and out of said heating zone.

KARL L. DIETRICH.
